Primary Examiner — Leanne Was-Englehart(57) **CLAIM**

The ornamental design for a hanger assembly, as shown and described.

DESCRIPTION

FIG. 1 is an exploded front, top perspective view of a hanger assembly, showing our new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another front, top perspective view of the hanger assembly, shown in an assembled configuration; and,

FIG. 10 is rear, bottom perspective view thereof, shown in an assembled configuration.

The broken lines in the figures illustrate portions of the hanger assembly that form no part of the claimed design.

1 Claim, 10 Drawing Sheets(56)
